Des. 231,646
Patented May 7, 1974

231,646

COFFEE URN

William M. Bardeau, 44 Princess Margaret Blvd.,
Islington, Ontario, Canada

Filed June 29, 1972, Ser. No. 267,611

Claims priority, application Canada Jan. 7, 1972

Term of patent 14 years

Int. Cl. D15—08

U.S. Cl. D94—3 B

FIG. 1

FIG. 2

FIG. 3

FIG. 4

FIG. 1 is a perspective view of a coffee urn showing my new design;

FIG. 2 is a reduced scale front elevation view;

FIG. 3 is a left side elevation view;

FIG. 4 is a top plan view.

The rear, not shown, is conventionally plain and unornamented.

I claim:

The ornamental design for a coffee urn, as shown and described.
